UNITED STATES PATENT OFFICE

WILLIAM D. LIPPS, OF FREDERICK, MARYLAND, ASSIGNOR TO OX FIBRE BRUSH COMPANY, INC., OF NEW YORK, N. Y., A CORPORATION OF DELAWARE

BRUSH MAKING MACHINE

Application filed February 16, 1932. Serial No. 593,272.

This invention relates to brush machines whereby brush backs are bored and wisps of fibre or bristles are successively removed from a magazine and transferred to a station 5 where each succeeding wisp is seated in a hole of a brush back and therein fastened by means of a wire staple.

The invention is more particularly designed for use in connection with machines for making floor sweeps and window and other brushes having relatively long flexible bristles with short folded butt portions which are secured to the brush back.

The object of the invention is to provide 15 simple and efficient mechanism whereby the tufts are inserted and stapled in the brush back with the upstanding butts of the respective tufts inwardly disposed at all points throughout the area of the back.

Another object of the invention is to provide 20 pneumatic means whereby during the insertion and stapling of each succeeding tuft in the brush back the opposing previously inserted tuft, irrespective of the direction 25 of travel of the brush back, is moved from the active path of the tuft inserting and stapling devices to permit such devices effectively to perform their respective functions.

With these and other objects in view my 30 invention comprises novel features of construction and combinations of parts which will be hereinafter described; the scope of the invention being expressed in the appended claims.

In the drawings—

Figure 1 is a side elevation of a brush making machine embodying my invention, showing the relation of the parts when the vertical cam element for effecting the operation 40 of the mechanism for partially rotating the tuft-setting spindle is in open or inactive position.

Fig. 2 is a similar view, enlarged, of a portion of the machine, showing the relation 45 of the parts when the said cam element is in closed or active position. In this view the spindle is shown in its down stroke and with its turning mechanism under the influence of the vertical cam element.

Fig. 3 is a view similar to Fig. 2, but look-

ing from the opposite side of the machine and showing in addition the bristle magazine and feeder. In Fig. 3 the turning mechanism for the descending spindle is shown as initially engaged with the vertical cam element. 55

Fig. 4 is a view similar to a portion of Fig. 3, but showing the spindle at the limit of its upward stroke.

Fig. 5 is a transverse vertical section, through the supporting frame adjacent the 60 spindle, as on the line 5—5 of Fig. 4.

Fig. 6 is a transverse horizontal section through the supporting frame in a plane through the spindle and the vertical cam element, as on the line 6—6 of Fig. 1. 65

Fig. 7 is a horizontal section in a plane directly above the pneumatic control valves, as on the line 7—7 of Fig. 2.

Fig. 8 is a detail, in perspective, of the valve actuating devices. 70

Fig. 9 is a similar view of the vertical cam element and actuating means therefor.

Fig. 10 is a sectional elevation of a portion of the spindle as carrying a staple and bristles to a brush back, when the back is 75 being advanced to the right during the filling operation, showing the staple driver and the tuft clamping lever, and also the air-blast nozzles and the action of the air-blast from one of the nozzles upon an opposing tuft 80 previously inserted in the back.

Fig. 11 is an elevation similar to Fig. 10 of the lower portion of the spindle and adjuncts when the back is being advanced to the left during the filling operation, showing 85 the action of the air-blast from the other nozzle upon an opposing tuft.

Fig. 12 is a view of the lower bifurcated end of the spindle, showing the staple bending anvil in section with a staple formed 90 thereon and seated in the spindle.

Fig. 13 is a section of a part of a brush back showing a positioned tuft as fastened thereto by the staple.

Fig. 14 is a plan of a brush back showing 95 the disposition of the tuft receiving holes therein.

Fig. 15 is a diagrammatic view of one end of the back, showing the angular disposition of the butts of the tufts and the staples there- 100

for, which tufts, for the sake of clearness, are represented in horizontal relation to the brush back with a series of end tufts as positioned thereon preparatory to stapling.

5 Referring to the drawings, 20 designates the supporting frame of a brush making machine; 21 designates a driven shaft and 56 designates a pattern cam mounted on the shaft.

10 22 designates a table on which the block 23 to form the brush back is supported, which table is intermittently actuated through suitable connections with the pattern cam, to feed the brush back to the active paths of 15 boring and tuft setting mechanisms, respectively. The latter mechanism includes a reciprocal vertical element 24 having at its lower or active end a bifurcated staple-forming and bristle-receiving portion, and also 20 containing a staple driver which is independently reciprocable in and longitudinally of said element.

25 25 designates a bristle-containing magazine, and 26 a horizontally reciprocative 25 feeder by means of which quantities of bristles are successively separated from the mass in the magazine and transferred to the tuft setting position.

30 Wire is intermittently fed to an anvil 27 which is periodically reciprocated to and from the vertical path of the element 24 in such manner that the bifurcated portion of the latter in its initial downward movement bears upon a section of wire and bends it over 35 the anvil to form a staple 28 which is snugly seated in such portion, as seen in Fig. 12. In the continued descent of the said element until its bifurcated portion bears against the brush back, the staple is caused to straddle 40 the end portion of a tuft of bristles positioned thereunder by the feeder 26. Thereupon the driver is forced downward to impinge against the staple and drive it into a hole of the brush back. The staple in its descent doubles 45 the end of the wisp and carries it into and fastens it in the hole of the brush back.

50 With the exception of certain novel features hereinafter described of the staple forming and tuft setting mechanism, the various mechanisms hereinbefore referred to are or may be of the general character described in the Young Patents Nos. 578,907 and 664,989, dated March 16, 1897 and January 1, 1901, respectively.

55 In previous machines the vertically reciprocative staple forming and tuft setting element was moved at all times in a straight path, whereas in accordance with one feature of the present invention the said element is partially rotatable about its vertical axis in such manner as to position the tufts and their associated staples in different angular relations in the brush back as required, thus enabling the folding of each wisp of bristles adjacent one end thereof and the

introduction of the folded end in the back with the butts of the bristles inwardly disposed at all points throughout the area of the brush back. (See Fig. 15.)

70 The form of tuft setting mechanism herein illustrated includes two vertically movable heads 29 and 30 which are slidably mounted in spaced parallel guide plates 31 on the upper overhanging portion of the supporting frame. The head 29 carries the staple forming and receiving element 24, and the head 30 carries the staple driver 32 which is reciprocative within and longitudinally of said element. The heads 29 and 30 are reciprocated vertically in any usual or approved manner. In the present instance the head 29 is connected by means of a link 33 with one arm of a rock lever 34 which is fulcrumed on the supporting frame and is connected by means of a link 35 with a peripheral lug on a cam 36 on an upper driven shaft 37 of the brush machine. The head 30 is connected by means of a link 38 with the arm 39 of a crank lever which is fulcrumed at 40 on the lever 34. The other arm 41 of this crank lever is provided with a roll 42 which runs in a fixed cam race 43 on the side of the supporting frame, said race being of such contour that during the oscillation of the rock lever 39 to effect the vertical reciprocations of its staple driver the crank lever is actuated to impart the requisite reciprocations to the heads 29 and 30.

75 80 85 90 95 100 105 110 115 120 125 130 In accordance with the principle of my invention the staple forming and tuft receiving element 24 carried by the head 29 comprises a pendant hollow spindle the upper end of which is rotatably mounted in the head 29. The lower portion of the spindle is reduced and bifurcated, as at 44, to provide a staple and tuft receiving foot whereof the inner vertical walls are grooved, as at 45, to support and guide the staple.

Fast on the spindle is a bevel gear 46 which is seated between the walls of a recess 47 in the head 29 and meshes with a gear segment 48 formed on or affixed to a rock lever 49 fulcrumed on the head 29. A spring 50 secured to one of the arms of the lever 49 and to the link 33 tends to maintain the rock lever in a normal horizontal position with the bifurcated end of the spindle in proper position to receive the staple and wisp, but when the lever is tilted more or less on its fulcrum the segment 48 effects the partial turning of the gear 46 and the attached spindle to vary the position of the bifurcated end of the latter and therewith the contained staple and wisp.

The means herein illustrated for tilting the lever 48 at stated intervals includes a hingedly-supported vertical plate 51 having adjacent its lower end a relatively long inclined cam portion 52 merging with a vertical portion 53, which portions, by actuation

of the plate, may be swung into or from the downward path of the free arm of the rock lever 49, as desired. This arm is provided with a roll 54 which abuts against the opposing cam portion 52 during the descent of the head after the staple has been formed and the tuft engaged by the lower end of the spindle, thus moving such arm upwardly and partially turning the gear segment 48 in a manner partially to rotate the spindle. As the head 29 continues and until it reaches the limit of its descent the roll 54 bears against the vertical portion 53 of the plate 51, which portion thus holds the rock-lever in the inclined position. In the ascent of the head 29, the roll escapes the cam portion 52 of the plate 51, whereupon the spring 50 returns the rock-lever and perforce the spindle to their normal or tuft-engaging position.

The periodical movement of the cam plate 51 with respect to the path of the rock lever 49 is effected through connections between the plate and a suitable control cam 55 on a driven shaft of the brush machine, which shaft in the present instance is the shaft 21 on which is mounted the usual pattern cam 56 for determining the various positions of the brush back table.

The cam plate 51 is supported by a pair of rods 57 projecting from a vertical shaft or pintle 58 which has its bearings in brackets 59 on the supporting frame 20. Projecting from the shaft 58 is an arm 60 which is connected by means of a link 61 with the upper arm of a vertical rock lever 62. This lever is pivoted at 63 on a bracket 64 on the supporting frame. The lower arm of the lever 62 is connected by a link 65 with the upper arm of a lever 66 which is fulcrumed at 67 on the frame 20, and the lower arm of the lever 66 is provided with a roll 68 which is held in operative contact with the control cam 55 by means of a suitably disposed spring 69. The peripheral contour of the cam 55 is such as to effect in conjunction with the spring 69 predetermined oscillations of the lever 66 to position the plate 51 with its cam portions 52 and 53 in or out of the path of the roll 68 of the rock lever 66 as any particular form of brush back may require.

In order to insure the horizontal setting of the rock lever 66 at the end of its upward stroke, should the spring fail to operate, an abutment 70 for the roll of such lever is arranged at the upper portion of the plate, which abutment preferably comprises the horizontal member of an angle piece 71 which is adjustably secured to the plate by screws 72 passing therewith through vertical slots 73 in the angle-piece.

During the descent of the spindle 28 while the machine is in operation the bristles engaged thereby are temporarily clamped in the spindle by a bifurcated foot 74 on the depending arm of a lever 75 which is ful-

crumed, as at 76, in a vertical groove 77 in the side of the spindle. A suitably disposed spring 78 interposed between the floor of the groove and the upper arm of the lever 75 urges the foot 74 to clamping position in relation to the bifurcated portion of the spindle. The upper end of the lever 75 is acted upon by a depending presser arm 79 which is pivoted at its upper end, as at 80, to a lug 81 on the head 29, which presser arm is reciprocated by and with the head. A spring 82 seated in a socket in the lug 81 bears against the arm 79 and urges it outward. On the outer edge of the arm is a projection 83 which during the non-rotative travel of the spindle 24 bears against the opposing vertical surface of a plate 84 fastened to the adjacent guide plate 31, thus forcing the presser arm 79 inwardly and swinging the clamping foot of the lever 75 outward to permit the bifurcated end of the spindle to receive the staple and the bristles. This done, the projection 83 escapes the lower end of the plate 84 immediately before the spindle is rotated, and in consequence the clamping lever 75 resumes its normal position and clamps the bristles. In the upward stroke of the spindle after the insertion of the bristles in the brush back the projection 83 of the arm 79 bears against the face of the plate 84 and returns the clamping lever 75 to its open or releasing position.

When the cam plate 51 is swung from its outer position to its full inner position, (as shown in full and dotted lines, respectively, in Fig. 6) the cam portions tilt the rock lever to such an extent as to impart a half turn to the spindle and the staple and tuft carried thereby, thus reversing the position of the butt end of the bristles with respect to the brush back; and when the cam plate is swung from its outer or inactive position to various active inner positions the cam portions tilt the cam lever to a corresponding smaller extent, thus imparting relatively smaller rotative movements to the spindle and the associated staple and tuft.

In Fig. 14 I have illustrated the back of a floor sweep showing the disposition of the tuft receiving holes therein. In the formation of these holes, and also in the insertion of the tufts therein, the operation in each case starts at the point *a* at one side of the back and midway between its ends, and continues intermittently throughout one half of the area of the back, as indicated by the successive arrows pointing from hole to hole until the point *b* is reached. In its travel in the longitudinal direction, indicated by the arrow *c*, the series of holes on one side of the median longitudinal line of the back are formed and the tufts inserted therein, and at the limit of this travel the row of holes *d* at the end of the back are formed and the tufts therein inserted until the point *e* is reached,

whereupon the direction of longitudinal travel of the back is reversed, as indicated by the arrow *f*. In this reverse travel the series of holes on the other or rear side of the median longitudinal line are formed and the tufts inserted therein, thus completing the filling operation in one-half of the brush back.

This done, the brush back is removed from its support and positioned thereon with the opposite end of the block reversed. The operation is then resumed, starting at the point *aa* and ending at the point *bb*, thus completing the filling operation.

During the tuft inserting operation on each portion of the area of the block face, the spindle first reciprocates in a straight path and positions each succeeding bunch of bristles with its butt end extending inwardly, so that when the bristles are inserted in the adjacent hole and stapled therein the butt end of the tuft is on the inner side of the upstanding tuft. When the end of the block is reached the cam plate 51 is swung partially inward to effect a partial rotation of the spindle sufficient to position the bristles with their butts extending inwardly of the brush back, the extent of rotary movement being determined by the contour of the end of the brush. When the end bristles have been inserted in the back, the cam plate 51 is swung fully inward and there maintained until the point *b* or *bb* is reached, as the case may be, depending upon which end of the block is being filled. Hence during this operation the bristles engaged by the spindle are given a semi-rotation so as to reverse the position of the butt end of each tuft with respect to the brush back, thus ensuring the inward disposition of the butts. (See Fig. 15.)

In accordance with my invention means is provided whereby the adjacent previously inserted upstanding tuft is moved from the active path of the spindle during the setting of each succeeding tuft, irrespective of the direction of travel of the brush back, so as to permit the free passage of the latter tuft to the surface of the back, which means is as follows:

Referring to Figs. 1, 2, 3, 7, 10 and 11, 85 and 86 designate two air blast tubes having their respective nozzles 87 and 88 located above the path of the brush back and directed toward opposite sides of the vertical path of the tuft setting spindle in a plane below the tops of the inserted bristles. The tubes 85 and 86 are connected to an air supply line 89 and are provided with normally closed valves 90 and 91, respectively, the reciprocable stems 92 of which valves are independently operable to permit the escape of air under pressure from either of the nozzles, as desired, thus blowing the opposing upstanding tuft away from the vertical path of the setting end of the spindle according to the direction of travel

of the brush back. To this end a pair of spaced toes 93 and 94 are movable laterally toward and from the tops of the respective valve stems in such manner that when one toe is directly above one valve stem the other toe is laterally away from the other valve stem. The two toes are affixed to and project from a shaft 95 which is slidable and rockable in a pair of bearings 96 in a suitably-disposed bracket 97 on the frame 20. One end of the shaft 95 is provided with an upstanding pin 98 which is engaged by the bifurcated arm 99 of a horizontally-disposed bell-crank fulcrumed on a bracket 100 on the frame 20. The other arm 101 of the bell-crank extends into the path of a vertical trip lever 102 pivoted, as at 103, on a laterally projecting bracket 104 on the link 65 which is included in the connections for operating the cam plate 51.

A suitably-disposed torsion spring 105 on the pivot of the trip lever tends to hold the latter in vertical position with its lower end in operative relation to the crank lever arm 101 and its upper portion in contact with a stop 106 on the bracket 104. Hence the spring pressed trip lever tends to maintain the bell crank in a normal position with the toes 93 and 94 in active and inactive relation to the respective valve stems 92. The relation of the parts just referred to is such that when the cam plate 51 is in inactive position in respect to the roll 54 on the rock lever 49 of the tuft inserting devices, the trip lever 102 depends in front of the crank arm 101, as seen in Fig. 8, and therefore when the link 69 is moved to swing the cam plate 51 to inward active position, as determined by the contour of the control cam 55, the depending trip lever 102 is correspondingly moved. In its initial movement the lower arm of the trip lever presses against and swings the opposing crank-arm 101, thus moving the shaft 95 longitudinally and shifting the toes 93 and 94 thereof to change their active and inactive positions relative to the adjacent valve stems. As the stroke of the link 65 and trip lever 102 continues, the lower arm of the trip lever rides over and escapes the crank arm 101; the latter and the shaft 95 together with the toes 93 and 94 thus resuming their normal condition. In the next succeeding stroke of the link 65 the trip lever 102 bears against the opposing crank arm 101 thus moving the arm and shifting the shaft 95 to return the toes 93 and 94 to their previous active and inactive positions relative to the respective valve stems 92, the trip lever riding over the crank arm 101 and assuming the position shown in Fig. 8.

At predetermined intervals during the operation of the machine the shaft 95 is rocked on its axis, thus causing the active toe to bear upon the underlying valve stem and open the associated valve. To this end the upstanding pin 98 on the shaft 95 is extended freely

through an eye 107 in the foot 108 of a vertical lever 109 which is fulcrumed, as at 110, on a bracket 111 on the frame 20. A spring 112 secured to the lever 109 and to the frame 20 tends to urge the lever to a position which maintains the toes 93 and 94 of the shaft 95 raised. The upper end of the lever 109 is curved, as at 113, into the path of a projection 114 on the cam 36 which effects the periodical reciprocations of the tuft setting and staple driving members. As these members approach the limit of their descent the projection 114 bears against the opposed curved end of the lever 109 and swings it outward, thus causing the lower arm of the lever through its flexible connection with the shaft 95, to rock the latter and swing the toes downward.

In the travel of the brush back shown in Fig. 14 between the points *a* and *e* and in the direction of the arrow *c*, the valve 91 is maintained open, and in consequence a continuous blast of air is ejected through the nozzle 88, thus forcing back the opposing upstanding tuft from the vertical path of the spindle in each succeeding tuft setting stroke, as indicated in Fig. 10. At the point *e* the valve 91 is closed and the valve 90 is opened and maintained in open position during the travel of the back in the direction of the arrow *f* to the point *b*, and in consequence a continuous blast of air is ejected through the nozzle 87, thus forcing back each opposing upstanding tuft from the vertical path of the spindle in each succeeding tuft-setting operation, as indicated in Fig. 11. The valves are similarly operated in timed relation to the reciprocations of the spindle during the filling of each half of the brush back.

It is to be understood that my invention is not limited to the particular construction disclosed, as the mechanisms may be modified within the principle of the invention and the scope of the appended claims.

I claim—

1. In a brush machine, the combination with a brush-back feeding table, means for feeding brush material to tuft-setting position, and a reciprocating tuft-setting tool for engaging the positioned brush material adjacent one end of the material, of means for oscillating said tool about its longitudinal axis at prescribed intervals during the tuft-setting operation.

2. In a brush machine, the combination with a brush-back feeding table, means for feeding brush material to tuft-setting position, an element having a bifurcated staple-forming and tuft-receiving portion, a staple driver in said element, and means for independently reciprocating said element and staple driver, of means for oscillating said element about its longitudinal axis at prescribed intervals during the tuft-setting operation.

3. In a brush machine, the combination with brush-back feeding mechanism including a table and a rotary pattern cam for determining the positions of the table, means for feeding brush material to tuft-setting position, and a reciprocating tuft-setting tool for engaging the positioned brush material adjacent one end of the material, of means for oscillating said tool about its longitudinal axis at prescribed intervals during the tuft-setting operation and including a rotary control cam in timed relation to the said pattern cam.

4. In a brush machine, the combination with a brush-back feeding table, means for feeding brush material to tuft-setting position, and a reciprocating tuft-setting tool for engaging the positioned brush material adjacent one end of the material, of means for oscillating said tool about its longitudinal axis at prescribed intervals during the tuft-setting operation and including a cam-engaging member reciprocable with the tool, a cam movable into and from the path of said member, and means for automatically shifting said cam.

5. In a brush machine, the combination with a brush-back feeding table, means for feeding brush material to tuft-setting position, and a reciprocating tuft-setting tool for engaging the positioned brush material adjacent one end of the material, of means for oscillating said tool about its longitudinal axis at prescribed intervals during the tuft-setting operation and including co-acting gear members reciprocable with the tool, a rock member for actuating one of said gears, a cam movable into and from the path of the rock member, and means for automatically shifting said cam.

6. In a brush machine, the combination with a brush-back feeding table, means for feeding brush material to tuft-setting position, and a reciprocating tuft-setting tool for engaging the positioned brush material adjacent one end of the material, of means for oscillating said tool about its longitudinal axis at prescribed intervals during the tuft-setting operation and including a gear member on the tool, a second gear member co-acting with the other member and reciprocable with the tool, a rock member for actuating the second gear member, a hingedly mounted cam member movable into and from the path of the rock member, and means for automatically swinging said cam member.

7. In a brush machine, the combination with a brush-back feeding table, means for feeding brush material to tuft-setting position, and a reciprocating tuft-setting tool having a bifurcated end for engaging the positioned brush material adjacent one end of the material, of means for oscillating said tool at prescribed intervals in the lower portion of its path of reciprocation, a tuft-

clamping member reciprocable with said tool and having a foot in cooperative relation to the bifurcated end of the tool, and means whereby the clamping member is periodically moved to clamping and releasing positions during the reciprocation of the tool.

8. In a brush machine, the combination with a brush-back feeding table, means for feeding brush material to tuft-setting position, and a reciprocating tuft-setting tool for engaging the positioned material adjacent one end of the material, of pneumatic means for delivering a blast of air against the opposing previously inserted tuft and thereby forcing such tuft from the active path of said tool during the setting of each succeeding tuft in the brush back, and including two spaced blast nozzles on opposite sides respectively of the path of the tool adjacent the back, and means for rendering either of said nozzles active or inactive in accordance with the direction of travel of the brush back.

9. In a brush machine, the combination with a brush-back feeding table, means for feeding brush material to tuft-setting position, a reciprocating tuft-setting tool for engaging the positioned material adjacent one end of the material, and means for oscillating said tool on its longitudinal axis at prescribed intervals during the tuft-setting operation, of pneumatic means for delivering a blast of air against the opposing previously inserted tuft and thereby forcing such tuft from the active path of said tool during the setting of each succeeding tuft in the brush back, and including two spaced blast nozzles on opposite sides respectively of the path of the tool adjacent the back, and means under the control of the tool oscillating means for rendering either of said nozzles active or inactive in accordance with the direction of travel of the brush back.

10. In a brush machine, the combination with a brush-back feeding table, means for feeding brush material to tuft-setting position, and a reciprocating tuft-setting tool for engaging the positioned material adjacent one end of the material, of pneumatic means for delivering a blast of air against the opposing previously inserted tuft and thereby forcing such tuft from the active path of said tool during the setting of each succeeding tuft in the brush back, and including a pair of air pipes having spaced blast nozzles on opposite sides respectively of the path of the tool adjacent the back, normally-closed valves for the respective pipes, pressure members for opening the respective valves, and means for actuating said pressure members to open either of said nozzles in accordance with the direction of movement of the brush back.

11. In a brush machine, the combination with a brush-back feeding table, means for feeding brush material to tuft-setting posi-

tion, and a reciprocating tuft-setting tool for engaging the positioned material adjacent one end of the material, of pneumatic means for delivering a blast of air against the opposing previously inserted tuft and thereby forcing such tuft from the active path of said tool during the setting of each succeeding tuft in the brush back, and including a pair of air pipes having spaced blast nozzles on opposite sides respectively of the path of the tool adjacent the back, normally-closed valves for the respective pipes, a longitudinally-movable rock-shaft, spaced pressure members on said shaft, an actuating member operatively connected with said shaft for longitudinally moving the shaft to position the pressure members in active and inactive relation to the respective valves, and means for operating said actuating member at prescribed intervals during the tuft-setting operation.

12. In a brush machine, the combination with a brush-back feeding table, means for feeding horizontally-disposed brush material to tuft-setting position, and a vertically reciprocating tuft-setting tool for engaging the positioned brush material adjacent one end of the material, of means for automatically effecting relative oscillatory movement between said tool and the table at prescribed intervals during the tuft-setting operation whereby the upstanding butt ends of the tufts can be positioned on the inner sides of said tufts throughout the area of the brush back.

Signed at Frederick, in the county of Frederick and State of Maryland, this 10th day of February, A. D. 1932.

WILLIAM D. LIPPS.
